UNITED STATES PATENT OFFICE

2,626,078

NONUPSETTING GARBAGE CAN

Clarence L. Hutchisson, Jr., and John D.
Spaulding, Mobile, Ala.

Application March 25, 1949, Serial No. 83,394

2 Claims. (Cl. 220—18)

1

Our present invention relates to improvements in the general class of metallic receptacles of the garbage handling type, and more specifically to a ground supported and non-upsetting garbage can having a fixed base for supporting and retaining the portable can in upright position, and from which base the can may readily be lifted for handling in the disposal of garbage or other contents. While the portable receptacle or can and its fixed supporting base in which the can is nested may be utilized for various purposes, the base is especially designed for use at, or above, the ground level as in a back yard, or the base may be installed flush with a pavement adjacent the curb of a street. In either position the base is adapted to receive and retain the lower portion of the portable can or receptacle, and the can and the base are equipped with coacting frictionally engaged means that prevent accidental overturning or upsetting of the can while supported in the base, thus insuring a stabilized and sanitary receptacle for the garbage or other material.

The portable receptacle and the fixed base each includes a minimum number of parts that may with facility be manufactured at low cost of production, the base may be installed with ease, and the can may be manipulated with convenience in mounting as well as in dismounting to and from the base.

The invention consists in certain novel features of construction and combinations and arrangements of parts as will hereinafter be described in detail and more particularly set forth in the appended claims.

In the accompanying drawings we have illustrated a complete example of a physical embodiment of our invention in which the parts are combined and arranged in accord with one mode we have devised for the practical application of the principles of our invention. It will however be understood that changes and alterations are contemplated and may be made in these exemplifying drawings and mechanical structures, within the scope of our claims, without departing from the principles of the invention.

Figure 1 is a view in elevation showing a metallic receptacle in which our invention is physically embodied; and Figure 2 is a bottom plan view of the receptacle.

Figure 3 is a plan view of a base in which our invention is involved; and Figure 4 is an enlarged fragmentary sectional view of the base.

Figure 5 is an assembly view partly in elevation and broken away for convenience of illustration.

2

Figure 6 is a plan view of a modified form of the base; and Figure 7 is a section thereof at line 1—7.

In order that the general arrangement and utility of parts may readily be understood, we have depicted a sheet metal can C, having the usual bail B for handling purposes, together with a customary lid L and its handle H.

In the process of manufacture the lower end of the cylindrical wall of the can is fashioned with a depending flange or skirt 1 projecting below a slightly elevated and flanged bottom 2 that is welded or otherwise secured within the can, and the skirt is braced or reinforced by means of a number of radially arranged and diametrically disposed vanes or blades 3 that are welded or attached in desired manner to the underside of the elevated bottom and to the inner face of the skirt.

Preferably, the lower annular edge of the skirt is serrated or scalloped, as at 4, and these serrations, when fashioned on the skirt, in addition to providing a wear-edge for the skirt, also perform the functions of cutters for loosening accumulated dirt or debris in the fixed supporting base of the can.

The upper portion of the skirt is equipped with an annular shoulder, bead, or collar, located preferably on the exterior of the skirt, which seats on the fixed base and provides a support for the can. In this specific form of the invention the annular supporting shoulder includes an exterior annular band 5 and its laterally projecting bead 6, and the exterior shoulder coacts with the interior flanged bottom of the can in providing a stable support on the can that seats on the upper face of the fixed base.

We have illustrated the base 1 as a rectangular block of concrete molded to shape, with a central opening 8 that not only economizes in the material used, but in addition the opening 8 provides a space to receive a filler of soil or other material, even with the upper face of the base.

The continuous, or annular groove 9 in the upper face of the base is of sufficient depth to receive the skirt, with the serrated edge of the skirt terminating just above the bottom of the groove, and the weight of the can being supported by the annular shoulder while the skirt is nested in the slot or groove. The annular slot or groove is of ample width for ready insertion into, and easy withdrawal of the skirt from the base; and sufficient clearance for the skirt is provided in the groove to permit a slight tilting of the can, as indicated by dotted lines in Fig. 5. Thus, in the event the nested can is accidentally bumped by

a pedestrian, or by a dog running down the street, the can may be tilted slightly to absorb the force of the bump without being dislodged, upset, or overturned, due to the retention of the skirt within the groove or slot.

To accommodate the radially extending braces 3 on the underside of the elevated bottom of the can, the base is fashioned with a number of radially arranged grooves 10 in its upper face, complementary to the braces; and these radially arranged grooves, which open into the annular slot or groove 9, also provide clean-out passages through which the dirt or debris may be scraped from the annular slot after it has been loosened by action of the serrated skirt as the can is turned in the annular groove.

Because of its heavy weight, a concrete base, when properly set in the ground, may provide ample rigidity as a support for the can or metallic receptacle; while under other conditions additional anchoring means are provided for stabilizing and rigidly retaining the installed base.

As here indicated the base may be anchored by the use of bolt holes 11 that are countersunk at 12 and adapted to receive spikes 13 having heads 14, which spikes are passed through the holes and driven into the ground for anchoring the base, and the lower ends of the spikes preferably are out-curved to insure a more tenacious fastening or anchorage for the base.

While we have herein illustrated and described a satisfactory arrangement of parts at the skirt or bottom portion of the metallic can, it will be understood that the annular supporting shoulder or bead of the can may be fashioned in other suitable manner, as for instance in Fig. 7, the metal of the bead may be crimped around an annular wire 15 to form the supporting shoulder or bead.

The slightly elevated bottom of the can may or may not be equipped with radial braces, the serrated bottom of the skirt may be optional, and as indicated in Fig. 7 the can may have a corrugated wall.

In the modified form of the base in Figs. 6 and 7, the hollow metallic and rectangular base 16 may be manufactured of cast metal, or stamped or pressed from sheet metal, and provided with an annular series of corrugations at 17 in the upper flat face of the base for reinforcing purposes.

In this cast metal, or sheet metal, base an annular depending and integral inner rib 18 forms the annular groove 9a in the flat upper face of the base for the reception of the skirt of the can or metallic receptacle, and the four radially arranged depressions or grooves 10a curve downwardly into the annular groove from the upper face of the base.

In addition to the countersunk spike holes 11-12 that receive the fastening spikes, additional anchoring means are provided for the metallic base, and these fastening means may be used singly, or jointly with the spikes shown in Fig. 5. For this purpose the metallic base is fashioned with four diagonally arranged anchoring plates as 19 that may be integral with, or attached to the base at its bottom portion, and these plates, or feet project an ample distance to provide a stable anchorage for the base. When the base is installed, these radially pro-

jecting anchors are covered by the surface soil, or sidewalk, and the open center of the base may be filled in with suitable material flush with the top of the base and the ground surface.

The different types of bases here shown may be manufactured in various sizes, or they may be manufactured with concentric annular grooves varying in diameter to accommodate cans of different sizes, and in some instances the base may be made adjustable for selective use with different sizes of cans.

Having thus fully described our invention, what we claim as new and desire to secure by Letters Patent is:

1. The combination with a rigid and fixed base having a flat top and an annular groove in its upper face, an open center, and a series of radially arranged grooves opening into the annular groove, of a portable can having an elevated bottom providing a depending skirt for the can, a series of radially arranged braces seated in the radially arranged grooves and located between the bottom of the can and its skirt, said skirt having a serrated free edge seated in the annular groove, and an exterior annular shoulder rigid with the upper portion of the skirt seated on the base.

2. A cylindrical garbage can having a lid and a hinged bail, an elevated bottom having an attaching flange and forming an annular skirt having a lower serrated edge, a series of radially arranged braces uniting the underside of the bottom and the inner face of the skirt, an exterior annular band attached to the skirt adjacent to the attaching flange, and a laterally projecting head on said band forming a supporting shoulder for the can.

CLARENCE L. HUTCHISSON, JR.
JOHN D. SPAULDING.
